UNITED STATES PATENT OFFICE.

LAURENT RONDOLIN, OF BERMONDSEY, LONDON, ENGLAND, ASSIGNOR TO PEEK
FREAN & COMPANY, LIMITED, OF LONDON, ENGLAND.

MANUFACTURE OF BISCUITS AND LIKE EDIBLE ARTICLES AND MEANS THEREFOR.

Application filed September 20, 1924. Serial No. 738,871

To all whom it may concern:

Be it known that I, LAURENT RONDOLIN, a subject of the King of Great Britain and Ireland, residing at Bermondsey, in the county of London, England, have invented Improvements Relating to the Manufacture of Biscuits and like Edible Articles and Means Therefor, of which the following is a specification.

10 This invention relates to the manufacture of biscuits and like edible articles according to which a plastic mass in sheet form is both impressed and cut, and more particularly to the manufacture of biscuits or their 15 equivalent by means of shell cutters within which work impression blocks or dies.

According to the present invention the manufacture as aforesaid is improved by arranging that the sheet mass shall be first 20 acted upon by the cutter to a limited extent and thereafter by the impression block or die. In this way the shell cutter acts to confine the mass sufficiently to prevent undue spread and consequently ensure enhanced 25 formation by the impression block or die.

A further feature of the improved method consists in causing the limited or partial cutting operation to be resumed only after the impression block or die has come to rest by which time all excess material will have been displaced beyond the knife edge of the cutters.

35 Yet another feature of the improved method consists in causing the biscuit blanks to be released from the action of the impression blocks or dies before the cutters are withdrawn from the sheet material.

The means for carrying out the invention may comprise any convenient arrangement of block and cutter heads and mechanism for securing the operations respectively referred to, but it is considered advantageous to impart motion to the cutter head through the companion head of the impression blocks, the two being resiliently connected together and movement controlling means being associated with the cutter head as hereinafter set forth.

50 But in order that the invention may be more readily understood it will now be further described with reference to the accompanying drawings whereof Fig. 1 is a part sectional elevation of so much of one constructional form of machine as is necessary to elucidate the action. Figs. 2 and 3 are

elevations at right angles thereto also with parts in section and removed. Fig. 4 is a collection of five diagrammatic views illustrating parts of such a machine in different positions as hereinafter explained with reference to the diagram Fig. 5. According to the example there are employed impression blocks *a* marginally recessed at *b* to produce, from dough, biscuits having up-standing rims or centres which are thinner than the edges. These impression blocks *a* are arranged within shell cutters *c* which are of well known type so that they at no time project therebeyond, the position at the commencement of a cycle of operations, as at A Fig. 4, being such that the blocks *a* are at a maximum distance from the edges of the cutters *c* and uncover vent holes *d* in the walls or shells of the cutters. The blocks proper *a*, ignoring the impression faces, may be of uniform cross section and pass through holes in a cutter head *f* which correspond in shape to the shape of the cutters *c* and be connected to a head *g* which either may be auxiliary to a beam *h* or itself constitute the beam, adapted to be positively operated or actuated, *i* representing the arms such as are customarily employed for the purpose.

The head f for the cutters may be separated from the head g or beam h for the impression blocks a by stiff springs such as shown at j Fig. 1, so that they move in unison except at times when means are brought into use to arrest or modify the movement. As exemplified, the cutter head f is connected by pillars k to plate m having tails n which work in guides o in the beam h , and are attached to screw threaded rods p passing through the latter and the springs j . The upper ends of the rods p are secured to a beam r provided with a pair of wearing plates s cooperating with a pair of edge check cams t driven in any suitable way as by bevel gearing u . Means such as bevel gearing v upon the beam r enables the position of the beam r to be adjusted by hand in relation to the members f , g , h — w being correspondingly adjustable stop nuts for determining the position of the head f in relation to the head g . 105

The whole arrangement is such that commencing with the initial position of the parts referred to, corresponding to A Fig. 4, the cutters *c* and impression blocks *a* ad- 116

vance collectively toward the sheet α of dough, there being no movement between the cutters and blocks until the cutters have entered the dough to the desired degree as at 5 B Fig. 4, when they are arrested by the cams t , the blocks a continuing to advance and any air which might tend to become imprisoned being released by the vent holes β . When the impression blocks a reach the end of their 10 stroke, position C Fig. 4, the cutters c are released by the cams t and rapidly complete their strokes under the action of springs j , position D Fig. 4, after which the impression blocks a commence their return stroke, 15 this continuing without movement of the cutters until the initial relative starting positions of the cutters c and blocks a are attained, position E Fig. 4, whereupon both cutters and blocks are moved in unison to 20 starting position. The foregoing action will be readily understood from the time-movement graph Fig. 5 when it is explained that the cams t make a complete revolution in the 25 time occupied by a double stroke of the machine and that the cams are shown in Figs. 1 and 2 as in position corresponding to interval numbered 7. Starting from interval 1 to midway of intervals 5 and 6 no relative movement occurs between the cutters and impression blocks, when the former are arrested by the cams. This arrest is absolute until interval 7 and the cam step is reached, due to the plates s bearing upon concentric 30 portions of the cams. The setting of the 35 nuts w is so chosen and the depth of the steps of the cams t made such that at interval 7 the cutters c will be arrested by the table y , whereon the dough sheet α is held, so that there is a clearance above the nuts 40 w and beam h , which is just sufficient to keep the cutters stationary until midway of intervals 8 and 9 when they move in unison again with the blocks a .

The beam h is shown as having journals 45 h^1 passing through sliding blocks h^2 to one of which one journal is normally latched as by the screw operated key h^3 Fig. 2, the arrangement being such that when the journals are free the various beams and heads

can be swung about the journals to enable 50 the cutters and impression blocks to be inspected or cleaned.

What I claim is—

1. A step in the method of manufacturing articles such as biscuits from a plastic mass 55 in sheet form, which consists in first subjecting the sheet mass to a cutting action, retarding such cutting action, impressing the mass whilst the cutting action is retarded and completing the impression before severance of the mass takes place, substantially as described.

2. A step in the method of manufacturing articles such as biscuits from a plastic mass 60 in sheet form, which consists in first subjecting the mass to a cutting action, arresting such cutting action before severance occurs, impressing the partially severed mass completely whilst the cutting action is arrested and finally resuming the cutting action to 70 complete the severance, substantially as described.

3. Means for manufacturing articles such as biscuits from a plastic mass in sheet form, 75 comprising a shell cutter and an impression die housed completely therein, means for advancing the die, resilient means through which the cutter is advanced by the die, and means for temporarily retarding movement of the cutter after it has partially advanced 80 into the sheet mass, substantially as described.

4. Means for manufacturing articles such as biscuits from a plastic mass in sheet form, 85 comprising a shell cutter and a companion die housed completely therein, means for advancing the die, resilient means through which the cutter is advanced by the die, and means for temporarily retarding movement of the cutter after it has partially advanced 90 into the sheet mass, the resilient connection between the cutter and die being adapted to ensure retraction of the impression die from the sheet mass before the cutter is withdrawn from such mass, substantially as described. 95

Signed at London, England, this 5th day of September 1924.

LAURENT RONDOLIN.
